SOLE LAYING MACHINE OR THE LIKE

Jacob S. Kamborian, West Newton, Mass.

Application October 25, 1952, Serial No. 21,984

Term of patent 14 years

(Cl. D55—1)

To all whom it may concern:

Be it known that I, Jacob S. Kamborian, a citizen of the United States of America, residing at West Newton, county of Middlesex, and Commonwealth of Massachusetts, have invented a new, original, and ornamental Design for a Sole Laying Machine or the like, of which the following is a specification, reference being had to the accompanying drawing, forming a part thereof.

Fig. 1 is a perspective view taken from the front and one side of a sole laying machine or the like embodying my new design; and

Fig. 2 is a perspective view taken from the front and other side thereof.

The rear wall not shown is substantially plain. The essential features of my design reside in the portions shown in full lines.

I claim:

The ornamental design for a sole laying machine or the like, substantially as shown and described.
